UNITED STATES PATENT OFFICE.

OLIVER J. MARSHICK AND EDWIN L. CROSBY, OF DETROIT, MICHIGAN.

REVERSING MECHANISM.

Application filed November 15, 1920. Serial No. 424,088.

To all whom it may concern:

Be it known that we, OLIVER J. MARSHICK and EDWIN L. CROSBY, citizens of the United States, residing at Detroit, county of Wayne, State of Michigan, have invented a certain new and useful Improvement in Reversing Mechanism, and declare the following to be a full, clear, and exact description of the same, such as will enable others skilled in the art to which it pertains to make and use the same, reference being had to the accompanying drawings, which form a part of this specification.

This invention relates to reversing mechanism for electric furnaces in particular, though adapted with little change for such analogous uses as effecting the oscillation of rotation of a churn, washing machine or tumbling barrel. It has for its object the provision of means for automatically reversing the direction of rotation of the drum after it has travelled through a certain angular space, adjustable according to the needs and circumstances of the particular use, if need be, while the drum is in motion.

In the drawings:

Figure 1 is an end elevational view of our improved mechanism, applied to a rotatable furnace drum;

Figure 2 is a large scale elevation with certain of the parts broken away or sectioned, of the component parts of our improved reversing mechanism;

Figure 3 is a large scale sectional elevation of our improved reversing mechanism, taken along the line 3—3 of Fig. 2, and

Figure 4 is a detailed elevation of several of the contact members, employed in our reversing mechanism.

1 represents the rotatable furnace drum, whose encircling track portions 2 rest upon the supporting rollers 3, thus taking the weight of the drum and its contents off from the connecting means between it and our reversing mechanism now to be described. Peripherally disposed about the drum, is a friction band or annular member 4, with which, in case gear teeth are employed, mesh the teeth of the motor-driven gear-wheel 5, which, like the nearby rollers 3, is rotatably supported in the base 6.

Near the bottom of the furnace drum is rotatably mounted the shaft 7 carrying the gear wheels 8 and 9, the former of which operatively engages the annular band 4 on the furnace drum in a way to reflect, in its

rotative movement, the rotative or oscillatory movement of the drum. The smaller gear wheel 9 lies within a slight irregularity in the shell or casing 10, with its teeth meshing with those of the large gear wheel 11 which is rotatably mounted on the shaft 12. From the forward face of the gear wheel 11 projects the pin or stud 13, which extends forwardly toward the gear member 15, in which are located a plurality of spaced holes 14, in any of which may engage the spring-projected pins 16 and 17, which are carried on the ends of the arms 18 and 19 respectively. Of these the arm 18 is keyed to the sleeve 20 on the shaft 12, whereas the arm 19 is similarly keyed to the outer sleeve 21, which is rotatable with respect to the sleeve 18. Each of these sleeves carries on its inner end a companion and correspondingly extending arm, as 22 and 23, so that, as shown in Figure 3, particularly, the outer arm 19, sleeve 21 and the inner arm 23 form a U-shaped unit. The corresponding parts 18, 20 and 22 are there shown only in end section, because, as brought out in Figures 1 and 2, the arms are there shown in position nearly at right angles to one another. Thus, as the angular distance between the two external arms 18 and 19, and their corresponding internal arms 22 and 23, is varied according to their position relatively to the series of holes 14, there are constituted on the wheel 15 projecting stops which limit the possible oscillatory path of the stud 13 on the gear wheel 11 with reference to the gear wheel 15, which, if the gear wheel 11 continues to move, must thereafter also move with it. If it does so, the engagement of its teeth with the teeth of the lower gear wheel 31 causes its rotation and consequently that of the shaft 32, on the forward end of which it is mounted, and which carries on its rear end the gear wheel 33 which meshes with the gear wheel 34 on the shaft 35. This latter shaft carries on its forward end (the left end as shown in Figure 3) the several contact blocks 36, which, as the shaft rotates, are swung into contact with one or the other of the spring-supported terminal blocks 37 and 38, each of which is connected by suitable wiring (which it is not thought necessary to here show) with the motor by which the rotation of the drum 1 is effected. The relative size of the several gear wheels is such that at the time the contact 36 is thrown against one or the other of the fingers 37

and 38 the toothed portion of the large-gear-wheel 11 within the casing has reached the extreme of its possible swing, and whatever slight further movement results is what is known as "coasting" and merely results in the drum contact 36 being moved slightly further onto the contact fingers 37 and 38. The making of this contact sets up a reverse current path through the motor from that under which it has been acting, and the turning of the train of gear-wheels in the opposite direction not only results in swinging the gear-wheel 11 within the casing in the opposite direction so that its stud 13 will encounter the other limiting arm set from that as regards its relative position, but, as well, throws the wheel carrying the contact-block 36 in motion toward the other spring-held contact pieces, as 38, thus once more reversing the direction of the current through the motor windings.

What we claim is:

1. In a reversing mechanism, in combination with a rotatable gear wheel operatively connected with a rockable furnace drum, a pair of adjustable limiting arms adapted to be fixed in position for engagement by a projecting portion of said gear wheel at the selected ends of its path of travel, a pair of oppositely disposed contact terminals, and a second gear wheel operatively connected with said first-named gear wheel, adapted to be rocked by the movement thereof into contact of a projection thereon against one or the other of said oppositely disposed contact terminals.

2. In combination with a plurality of oppositely disposed contact terminals, an oscillatory contact piece adapted to engage one or the other of said contact terminals when moved in either direction from neutral position, a plurality of rotatable gear wheels connecting said oscillatory contact piece with a rockable furnace drum, and adjustable limiting members adapted to interfere with the rotation of one of said gear wheels when

the end of its desired path of travel has been reached.

3. The combination, with a connection to a source of rotative actuation, of a rotatable gear member, a plurality of independently adjustable limiting members whereby the length of the path of travel thereof may be regulated, a pair of oppositely disposed contact terminals, and means operatively connected with said rotatable gear member adapted to be rocked in consonance with the direction and degree of oscillation thereof into contact with one or the other of said contact terminals.

4. In combination with a rotatable shaft operatively connected with a rockable furnace drum, a pair of oppositely disposed terminals, an oscillatory contact member operatively connected with said rotatable shaft and adapted to be swung by the actuating movement received therefrom against one or the other of said terminals, a rotatable gear member with which said oscillatory contact member is connected, and adjustable means adapted to act upon said rotatable gear member for regulating the degree of its possible movement.

5. In combination with a plurality of contact terminals, an oscillatable contact piece adapted to engage one or the other of said terminals when swung a sufficient distance in either direction from its intermediate position, means for operatively connecting said oscillatable contact piece with a rotatable furnace drum, and means capable of adjustment relatively to one another and to certain of said last-mentioned means whereby the degree of possible movement of certain of said parts may be regulated.

In testimony whereof, we sign this specification in the presence of two witnesses.

OLIVER J. MARSHICK.
EDWIN L. CROSBY.
